UNITED STATES PATENT OFFICE.

RAYMOND C. SCHLORE, OF CHICAGO, ILLINOIS.

SPRING JACK.

Application filed November 15, 1926. Serial No. 148,511.

My invention relates to spring jacks and has to do more particularly with apparatus of the above character adapted for use as a spring jack to act as a socket for holding 5 audion tubes, but of course not limited to this particular use.

An object of my invention is to provide a device of the above character which is simple in construction, cheap to manufacture 10 and readily applied. Another feature of my invention is that it may be used in the form of an elongated bar or frame having the jack springs mounted along in spaced relation, providing a number of positions so 15 that the audion tubes, or other devices adapted to be applied thereto, may be readily mounted in alignment as is frequently desirable, particularly in radio receiving sets.

For a better understanding of my invention reference is to be had to the accompanying drawing, in which—

Fig. 1 is a side elevation of the preferred form of spring jack showing an audion tube inserted in one of the jacks;

25 Fig. 2 is a top plan view of Fig. 1;

Fig. 3 is an enlarged top plan view of Fig. 1 to show the spring and terminal arrangement more clearly;

Fig. 4 is an end view of Fig. 3; and

30 Fig. 5 is a top plan view of a section of the jack showing a modified form in which the guiding recesses are provided in the frame rather than in the jack springs.

Referring now more in detail to the form 35 of invention shown in Figs. 1 to 4, I provide a suitable frame A preferably in the form of an elongated rectangular insulating bar having a plurality of spaced positions each provided with a spring jack for receiving 40 an applied device such as an audion tube T.

These spring jacks are preferably all of the same construction and a description of one will suffice for all. These jacks include jack springs mounted upon opposite faces 45 as 6—7 of the frame A and extend to a point adjacent an abutting face 8 adapted to act as a stop for the audion tube or other device applied thereto. These jack springs are spaced so as to provide sufficient clearance 50 between them, and to this end the springs as 9 are vertically disposed and each secured by a suitable terminal screw or binding post 10. The opposite springs 11—12 are angularly disposed so as to position the corresponding 55 terminal screws or binding posts 13 sufficiently away from the post 10 to provide

proper clearance and insulation between the parts and to prevent any inductive flow of current.

In order to properly receive the terminals 60 of the tube T when applied to the jack, I provide recesses adapted to receive the terminals so as to not only guide the tube terminals when applied, but also prevent any movement of the tube along the bar after its 65 terminals are inserted in the jack.

The tube T shown is of the ordinary standard type having four projecting terminals, thus corresponding with the four jack springs of each jack. In the form of my 70 invention as shown in Figs. 1 to 4 these recesses are formed at 14 in the ends of the jack springs. In other words, the jack springs are rounded at the terminal receiving ends so that the terminals will slide into the 75 recesses.

In order to prevent any rotation of the tube upon the jack frame I preferably arrange the bar 8 of a thickness so that the terminals will just fit over the bar and slidingly engage the spring ends when inserted. Also in order to lighten the bar or frame A and also reduce the losses otherwise occurring across the springs, I provide openings 80 as 15 through the wall thereof, thus providing a support in the nature of a skeleton frame.

It will thus be seen that I have provided a spring jack in the form of an elongated member adapted to be secured in any suitable way to the base of the radio receiving set and the wiring readily connected to the various terminals of the jacks. Also by the arrangement provided the tubes are aligned in the receiver, which is usually a 95 desirable method of mounting them.

In Fig. 5 I have shown a modified method of recessing the elements to guide the tube terminals, and to this end the recesses are in the form of slots 14' cut into the side faces 100 of the frame. The jack springs may then be straight faced as shown in Fig. 5, or recessed as shown in the other form. When constructed with the recesses in the frame A as in Fig. 5, these recesses are so spaced 105 that the tube terminals will be slidingly received therein and held against displacement along the frame.

What I claim as new and desire to secure by United States Letters Patent is:—

110 1. A spring jack including a rectangular insulating bar, jack springs mounted upon

opposite sides of the bar with terminal receiving ends adjacent a free edge of the bar, said springs being adapted to fixedly receive extending terminals of an applied device on opposite sides of the bar between the springs and the sides of the bar.

2. A spring jack including a rectangular insulating bar, jack springs mounted upon opposite sides of the bar with terminal receiving ends adjacent a free edge of the bar, said springs being adapted to fixedly receive extending terminals of an applied device on opposite sides of the bar between the springs and the sides of the bar, there being a recess provided for each spring end and adjacent face portion of the bar to guidingly receive and hold a received terminal against movement along the bar.

3. A spring jack including a rectangular insulating bar, jack springs mounted upon opposite sides of the bar with terminal receiving ends adjacent a free edge of the

bar, said springs being adapted to fixedly receive extending terminals of an applied device on opposite sides of the bar between springs and the sides of the bar, said spring ends being provided each with a recess to receive the applied terminal to prevent movement of the applied device along the bar.

4. A spring jack including a longitudinal rectangular frame having an abutting edge, spaced four-terminal-audion-tube receiving positions along the bar, jack springs mounted upon opposite sides of the bar at each position and having tube terminal receiving ends adjacent the abutting edge, whereby the terminals of an applied tube are inserted between the spring ends and adjacent face of the bar with the tube base abutting the abutting edges of the bar.

In witness whereof, I hereunto subscribe my name this 8th day of November, 1926.

RAYMOND C. SCHLORF.
